UNITED STATES PATENT OFFICE.

WILLIAM C. FISHER, OF MIDDLETON, CONNECTICUT, ASSIGNOR TO THE RUSSELL MANUFACTURING COMPANY, OF MIDDLETON, CONNECTICUT, A CORPORATION OF CONNECTICUT.

PROCESS OF MAKING SELVAGED-EDGED FABRICS.

Application filed August 14, 1922. Serial No. 581,848.

The present invention relates to a process of making an endless fabric strip without transverse joints and with selvaged edges from a simple piece of tubular fabric and to provide a novel means forming the selvaged edges thereof.

In certain methods of making endless belts it has been customary to use a plurality of short separate individual sections of a tubular fabric, the entire fabric folded inwardly at the edges with one tube placed inside the other with the folded in edges face to face and arranged in a lap joint or to use a simple tube with a double fold and thereupon to 15 stitch the entire structure to secure the folded edges of each section of the tube together and also connecting the two tubes. This method, however, has disadvantages in requiring the employment of two tubular sections or an 20 entire double fold of a simple strip and is relatively expensive, requires a large amount of stitching and has other attendant disadvantages of a possible variation in the tension of the stitching tending to warp the 25 completed article, and moreover, no means is provided for assuring alignment or longitudinal parallel extension of the threads of the fabric forming the endless strip or belt.

It is an object of the present invention to 30 provide a process by which a selvaged edged endless strip may be formed from a single tubular section of fabric with a novel means of forming the selvaged edges, the present invention further contemplating the formation 35 of a plurality of such individual endless strips from a wider blank as will herein-after appear.

A further object of the present invention relates to a process of making an endless 40 strip of the character indicated in which the body portion is changed at the edge forming portions to provide a selvage edge material of substantially the same thickness when the edges are turned in, as the body portion 45 of the strip, as, for example, dropping the binder of the body portion at these edge portions or by a modification of the thickness of the threads used at the selvaged edges.

It is a further object of the present invention to provide a process of forming such 50 an endless fabric with the selvaged edges thereof formed along a line of the thread of the body portion of the strip or belt, as this forms an added advantage among others,

that the completed article will run true when 55 used as a belt for example and this formation of the selvaged edge along a thread of the body portion of the fabric may be readily attained independently of a possible variation in the curvature of the threads due to the 60 weaving in the loom which curvature usually occurs as will be understood by those skilled in the art.

A still further object is to make a plurality of endless belts from a blank having 65 spaces of different thickness of material for forming the selvaged edge portions and then cutting and turning this material in a single or in separate operations in such a manner as to form the selvaged edge for the strip. 70

Various other objects are within the scope of this invention such as relate to the method of accomplishing the results obtained; to the various details which may be advantageously employed if desired; to the steps in 75 which the economies of manufacture referred to are obtained as wherein a belt may be provided from a single tubular strip of fabric and selvaged edges formed thereon, which may be conveniently cut from a large 80 blank containing a plurality of belts and the selvage edges turned to produce the completed structure by the simplified steps set forth, eliminating the disadvantages of certain prior methods; and to numerous other 85 features which will be apparent from a consideration of the drawings and the related description of the form of the invention which may be preferred, in which—

Fig. I illustrates a strip of tubular fabric 90 from which a plurality of endless strips or belts may be made in accordance with the present invention.

Fig. II is an enlarged diagrammatic view 95 along a line corresponding to the line 2—2 of Fig. I in which the binder threads are dropped below the lower ply, thus differing from the embodiment illustrated in Fig. I, in which the binder threads are brought out along the face of the material.

Fig. III is a view similar to Fig. I, illustrating the formation of the individual sections and selvaged edged portions.

Fig. IV is an enlarged diagrammatic view 105 on the line 4—4 of Fig. III, showing how the folded selvaged edges are arranged in carrying out the process.

Fig. V is a plan view of an endless strip

cut from the fabric illustrated in Fig. III showing the action of the strip cutting and folding tool which may be used.

Fig. VI is a sectional view of the tool on the line 6—6 of Fig. III.

Fig. VII is a perspective view of the completed endless strip of belt.

Fig. VIII is a view on the line 8—8 of Fig. VII.

10 Fig. IX is a view of a modification of the type of tool which may be employed if desired.

15 Referring to the drawings in Fig. I, I have shown a strip of tubular fabric 10, formed in the particular embodiment illustrated herein as having an upper ply 12 and a lower ply 14 with a binder material 15 as illustrated in Fig. II. At intervals along the tubular woven strip 10, which may be of 20 any width and length, the binder material 15 may be dropped and brought out along the face or base of the material as indicated at 16 in Figs. I and II respectively during the weaving operation, the dropping of the 25 binder occurring along the straight line of the threads 20 and 21 of the body portion of the fabric 10 as will be apparent to those skilled in the art. It is moreover apparent that this dropping will occur along this line 30 irrespective of any curvature in the position of the threads formed during the weaving operation, as it is known that a slight curvature in the threads takes place in weaving.

35 As shown in Fig. III the dropped binder portion 15 of the material 10 is now cut away with a flat wide doubled edge hand tool 17 to eliminate the binder or gutting sections 16 of the strip. The thickness of the material 40 at the portion 18 will be therefore reduced and formed of the top and bottom plies of the material 10, it being intended to form the selvaged edges of the individual strips from this reduced portion.

45 The fabric may now be cut along the center of selvage edge forming portions 18 as shown in Fig. III with a suitable tool 19 for that purpose which is preferably of such size and shape, at least at a portion thereof, as to 50 substantially fill the portion between the threads 20 and 21 between the upper and lower plies 12 and 14 when the tool is inserted therein. The tool 19 is provided with a cutting edge and folding attachment to simultaneously cut the individual endless belts and fold the selvaged edges temporarily in 55 proper position. The cutting edge, such as a wheel 22 on the tool 23, is thus preferably located midway of the side edges of the tool so that the strip 18 is cut substantially in 60 the center so that a plurality of equal belt sections 10' will be cut from the blank 10 and each will be provided with selvage forming edges, one for each strip, of such width 65 that when folded in on itself will meet the

body thread 20 of the body portion of the strip. The type of suitable tool 17, such as that disclosed herein is claimed in my Patent No. 1,483,425 filed of even date herewith, although other tools may be used for cutting the strip 18 to form adjacent selvage edges of adjacent strips.

A suitable folding attachment illustrated at 24 may be employed to fold the cut edges of the upper ply 12 and lower ply 14 inwardly upon itself as illustrated in Fig. IV to form, when secured together, the selvaged edge of the fabric. Thus the tool may be provided with four folders, 25, 26, 27 and 28 and fold, if desired, the upper and lower 50 plies of the selvaged edge for two adjacent strips simultaneously which action will result when the tool 19 is inserted in the portion 18 and forwardly advanced between the upper and lower plies around the entire tubular strip 10 returning to the point of commencement to simultaneously cut the upper and lower plies 12 and 14 of the strip 18 along the center thereof and fold the upper plies 12 inwardly on itself and the lower plies 14 likewise inwardly on itself as indicated in Fig. IV.

The individual strips from the blank 10 will thus be formed when the several sections 18 are cut, forming endless separate 95 belts as illustrated in Figs. VII and VIII of a single fabric piece with the selvage edge now in folded position. The sections 10' are now stitched along the turned selvaged edges of both plies to secure the same together to form the complete article. Instead of stitching, the selvage edges may be permanently secured with a glue composition or rubber cement or the like.

Moreover, it is apparent that if desired a 105 suitable size or glue may be employed and applied to the turned edges 12' and 14' of the upper and lower plies 12 and 14 during the cutting and folding operation in order to temporarily retain the folded selvaged edges in position previous to the stitching. To this end I have illustrated in Fig. IX a tool in which a suitable opening adjacent the forward end thereof is provided through which glue may be forced, 110 there being a reservoir 30 connected with the tool and a pipe 31 leading from the reservoir to the opening at the forward end of the tool by which the size may be applied to the edge portions of the upper and lower plies 115 12' and 14' during the cutting operation, the glue oozing through the fabric sufficiently so that when folded by the folding attachment the same will satisfactorily retain the folded selvaged edges in place.

120 It will thus be seen that I have provided a simple and efficient process for forming a selvaged edged endless strip which may be readily employed in making a plurality of similar or dissimilar endless strips from a 130

blank depending on the location and width of the dropped sections 18 and the proper sized cutting and folding tool which will be used accordingly. The process can be carried out on a blank by dropping and cutting out the binder, for one strip only then cutting the individual strips and folding the edges for one strip instead of for two adjacent strips as shown herein, in which case the 10 material adjacent a cut out belt could be used for other purposes, or otherwise operated upon to form an endless strip, if desired.

Reference is hereby made to my Patents Nos. 1,429,630 and 1,483,425, granted on co-pending applications and relating to the article and tool referred to herein.

It is apparent that within the spirit of the invention modifications and different arrangements may be made other than as hereinafter disclosed, and the present disclosure is illustrative merely, the invention comprehending all variations thereof.

Having thus described my invention, what I desire to secure by Letters Patent of the 25 United States and claim is:

1. A process of making a plurality of end-

less fabric strips that comprises making a tubular piece of fabric having an upper ply, a binder, and a lower ply, dropping the binder threads thereof at spaced intervals to form edge forming portions of the upper and lower plies, cutting away said dropped binder threads, cutting the fabric blank through the edge forming portions to form individual strips and folding each edge portion of the upper and lower plies inwardly to form the selvaged edge and securing the folds and plies together at the edge portions.

2. A process of making an endless fabric 40 selvaged edged strip that comprises making a tubular piece of fabric consisting of a plurality of plies and a binder interconnecting annular segment portions of the plies, cutting the binder and plies at the non-interconnected portions; folding in the edges of the cut plies to form the selvaged edge; securing the folds in place by cement and stitching the edge portions.

In testimony whereof, I affix my signature.

WILLIAM C. FISHER.
